UNITED STATES PATENT OFFICE.

JOHN F. O'ROURKE, OF NEW YORK, N. Y.

MEANS FOR SUPPORTING TUNNEL-LINING SEGMENTS.

1,382,668.

Specification of Letters Patent. Patented June 28, 1921.

Application filed November 8, 1919. Serial No. 336,729.

To all whom it may concern:

Be it known that I, JOHN F. O'ROURKE, a citizen of the United States, and resident of New York city, borough of Manhattan, 5 in the county of New York and State of New York, have invented certain new and useful Improvements in Means for Supporting Tunnel-Lining Segments, of which the following is a specification.

10 Heretofore in erecting tunnel linings the practice has been, in the case of cast iron lined tunnels, to connect each segment of a new ring or arch to the last erected ring by means of screw bolts through the circumferential flanges and similarly to bolt the 15 ends of the segments to one another in the longitudinal joints. In the case of lining comprising concrete blocks having projections and recesses the projections of one block entered the recesses in another block 20 or blocks of the previous ring or arch as the new ring segments were installed and the newly erected blocks were held in place by jacks of the shield until the completion 25 of the ring. In addition to the foregoing shores and tie rods were used to hold the lining in position and form.

The object of my invention is to support 30 each segment or block of the upper part of the tunnel lining ring or arch as soon as erected and to hold the same in its true position for a desired period while all the other segments or blocks of the ring or arch are being erected.

35 In carrying out my invention I provide beams or bars extending longitudinally within the end portion of the tunnel lining being erected, and I support said beams against several of the adjacent erected rings and 40 against the new segments of the ring being erected in the true cylindrical surface required by the tunnel plans. Any desired number of said beams may be used in connection with the installation of a tunnel lining and in such a manner that the combined 45 action of such beams will be such that any ring or segment can, by adjustment of such beam or beams in coöperation therewith, be corrected for departure from position or 50 true cylindrical surface and supported in same until permanently held, as by packing, such as gravel, used exterior to the ring in the space between the outside of the tunnel lining and the wall of the excavation containing it.

55 My invention further comprises novel de-

tails of improvement and combinations of parts that will be more fully hereinafter set forth and then pointed out in the claims.

Reference is had to the accompanying 60 drawings forming a part thereof wherein—

Figure 1 is an end elevation illustrating my improvements within a tunnel lining;

Fig. 2 is a longitudinal section;

Fig. 3 is an enlarged fragmentary view 65 of part of Fig. 1;

Fig. 4 is a section on the line 4—4 in Fig. 3;

Fig. 5 is a perspective sectional detail view;

Fig. 6 is a sectional detail of a modification, and

Fig. 7 is a cross section thereof.

The tunnel lining illustrated in the accompanying drawings comprises segments or blocks 1 arranged end to end in ring-like form, which may be of any usual construction. In the form shown the segments 75 1 have projections 2 on one side and recesses 3 on the opposite side, the projections of one segment or block entering the recesses 80 of the adjacent segment or block in a well known manner, such as disclosed in Letters Patent granted to me November 5, 1912, No. 1,043,348. When the blocks are erected it is customary to install the lower central 85 block and apply the other blocks in position in an upward direction, so that the blocks being installed above a horizontal line have been temporarily retained in the manner first before described, but there 90 has been a tendency for such blocks to depart from the desired position or true cylindrical surface, as when the retaining jacks of the shield have been removed from the blocks. To support blocks of one or more 95 rings that have been installed as well as to support blocks of a ring being installed I provide beams or bars 4 supported to extend longitudinally within a tunnel lining in contact with such blocks, to sustain them in 100 position or restore them to true position in case of deviation therefrom.

In the example illustrated I provide a frame 5, which may be of any suitable construction, adapted to rest upon the bottom portion of a tunnel lining, and shown having beams 6 and arch-like members 7 spaced from the inner surface of the tunnel lining to support the beams or bars 4. Member 7 is shown comprising a channel-like bar 8 110 suitably curved or arched and having its ends anchored to beam 6 of frame 5. By

preference I provide plates 9 secured to and depending along the sides of bar 8 and which may be riveted thereto, whereby a strong arch-like member is provided. Tie bars 7^a 5 rigidly connect the spaced members 7. The beams 4 are supported upon the members 7 for adjustment toward and from the tunnel lining, and said beams also are preferably longitudinally adjustable on the members 7 10 independently of the adjustability of frame 5 longitudinally within the tunnel. The beam supporting members 7, as shown in Figs. 1 to 5, carry screws 10 shown, operative in nuts 11 secured to member 7, which 15 screws are adapted to operate against the inner sides of beams 4 to move said beams toward the tunnel lining to adjust and retain the segments thereof. The beams 4 are shown guided for longitudinal and perpendicular movement in brackets 12 shown secured upon the beams 8 of members 7 by rivets. The bars 4 are shown in the form of I-beams having their inner flanges within the brackets 12 and their outer flanges adapted 20 to bear against segments or blocks 1. The beams 4 may be provided with hand grips 13 to permit their ready adjustment in a longitudinal direction. While the beams 4 could slide directly upon the members 7 I 25 prefer to provide anti-friction rolls 14 upon which the beams 4 may run freely. Said rolls are shown carried by pivots 15 journaled in spaced brackets 16 riveted to side plates 9 of arch-like members 7. In the example 30 illustrated in Figs. 1 to 5 a screw 10 and a roll 14 is provided upon each arch-like member 7 for each bar 4 spaced and disposed in the longitudinal direction of the tunnel, so that the two sets of screws may operate 35 at different distances apart upon a beam 4, and the latter may roll upon such spaced rolls for longitudinal adjustment. Means other than screws may be provided to move the beams 4 toward the segments 1 and to 40 retain said beams in set position. In Figs. 6 and 7 a cam-member 17 is mounted upon a pin or shaft 18 carried by plates 9 of member 7, said cam-member preferably being provided with a handle 17^a for its operation. 45 Said members 17 will be mounted upon supporting members 7 in relation to the beams 4 to operate and retain them. By rotating the cam-members 17 in one direction the beams 4 will be appropriately moved against 50 the segments 1 and be there retained, and by rotating said cam-members reversely the beams 4 will be released from the segments. 55 In accordance with my improvements the beams 4 may be set by screws 10 or cam-members 17 to bear against segments or blocks of rings that have been erected to 60 retain them in position and when the segments or blocks of a new ring have been erected up to the spring-like or transverse center of the tunnel the adjacent beams 4 65 may be advanced and set by the screws 10 or members 17 against the latter segments or blocks before the erector is detached therefrom. As each upper segment or block is placed in position the corresponding beams 70 4 will be moved longitudinally to extend along such segment and will be adjusted outwardly by the screws 10 or members 17 to engage said segment to retain it in its proper position before the erector is detached from 75 the segment. After all the segments or blocks of a ring of the lining have been set similar adjustment of beams 4 will be made for the blocks of a new ring to be set, and when necessary the frame 5 will be moved 80 forwardly and the beams 4 set in required position to permit the erection of the segments or blocks of a new ring, and so on. The beams 4 being of sufficient length to coöperate with several of the rings erected will 85 bear against the latter as well as against the new segments being erected, so that the latter may be maintained in the same cylindrical surface as the erected rings while in contact with the beams. By reason of the 90 independent adjustability of the several beams their action is such that a ring segment can be corrected for departure from desired position or true cylindrical surface by a simple adjustment of the appropriate 95 beam or beams, whereby to prevent any segment from displacement inwardly of the tunnel lining. One or more beams 4 may be used for a segment being erected. The beams 4 may maintain the segments or blocks 100 in proper position until the space around the lining within the excavation in the ground is charged with packing, such as gravel, as in accordance with Letters Patent granted to me on July 31, 1917, No. 1,235,233, 105 whereby displacement of the rings and segments thereof is prevented when the beams 4 are being adjusted and release the segments.

Having thus described my invention, what 110 I claim and desire to secure by Letters Patent is:—

1. A support for tunnel lining segments comprising a frame having spaced guiding means, a beam movable in said guiding means, and means carried by said frame to retain said beam set against said segments.
2. A support for tunnel lining segments comprising a frame having spaced supporting members, spaced guiding means on said 120 members, a movable beam in said guiding means, and means on said members coöoperative with said beam to retain it set against said segments.
3. A support for tunnel lining segments 125 comprising a frame having spaced arch-like members, spaced guiding means on said members, movable beams in opposing guiding means to extend longitudinally respecting the tunnel lining, and means upon said 130

- members to retain said bars in set position to support said segments.
4. A support for tunnel lining segments comprising a frame having spaced arch-like members, spaced guiding means on said members, movable beams opposing guiding means to extend longitudinally respecting the tunnel lining, and means upon said members operative to move said bars toward said segments and retain the bars in set position.
5. In a tunneling device, a beam, a support for said beam, and means on the said support for adjusting the vertical position of said beam.
6. In a tunneling device, a beam, a support for said beam, and means on the said support for adjusting the vertical position of said beam and for clamping the same in position.
7. In a tunneling device, a beam, a support for said beam, and means on the said support for adjusting the vertical position of said beam, the said support comprising arched members.
8. In a tunneling device, a beam, a support for said beam, and means on the said support for adjusting the vertical position of said beam, the said beam extending longitudinally of the tunnel.
9. In a tunneling device, a beam, a support for said beam, means on the said support for adjusting the vertical position of said beam, and means for securing the beam in position whereby it may be shifted longitudinally of the tunnel.
10. In a tunneling device, a beam, a support for said beam, and means on the said support for adjusting the vertical position of said beam, the said means for adjusting the position of said beam comprising a screw jack passing through said support.
11. In a tunneling device, a beam, a support for said beam, means on the said support for adjusting the vertical position of said beam, and anti-friction means on said support under the said beam.
12. In a tunneling device, a beam, a support for said beam, means on the said support for adjusting the vertical position of said beam, and anti-friction rollers on said support under the said beam.
13. In a tunneling device, a beam, a support for said beam, means on the said support for adjusting the vertical position of said beam, the said beam extending longitudinally of the tunnel, and a handle on said beam.
14. In a tunneling device, a beam, a support for said beam, and means on the said support for adjusting the vertical position of said beam, said support comprising a traveling platform having means on the side thereof for exerting pressure on the sides of the tunnel.
15. In a tunneling device, a beam, a support for said beam, and means on the said support for adjusting the vertical position of said beam, the said support comprising a traveling platform, means on the side thereof for exerting pressure on the sides of the tunnel, the said means for exerting pressure on the sides of the tunnel comprising a swinging beam and means for thrusting the same outwardly.

Signed at New York, in the county of New York and State of New York, this 5th day of November, A. D. 1919.

JOHN F. O'OURKE.
